[57] **CLAIM**

The ornamental design for a ball dropping device for batting practice, substantially as shown and described.

DESCRIPTION

FIG. 1 is a front perspective of a ball dropping device for batting practice showing our new design;

FIG. 2 is a sectional view taken along the line 2—2 of FIG. 1;

FIG. 3 is a perspective view from the opposite side of FIG. 1;

FIG. 4 is a bottom plan view;

FIG. 5 is a rear elevation;

FIG. 6 is a side elevation opposite FIG. 3;

FIG. 7 is a top plan view.

FIG. 2

FIG. 1

FIG. 5

FIG. 7

FIG. 6
